CLAIM

The ornamental design for an LED boom, as shown and described.

DESCRIPTION

FIG. 1 is a perspective view of an LED boom according to another embodiment of the present design;

FIG. 2 is a right side view of FIG. 1;

FIG. 3 is a left side view of FIG. 2;

FIG. 4 is a top view of FIG. 3; and,

FIG. 5 is a bottom view of FIG. 4.

The broken line disclosure represents portions of the boom which form no part of the claimed design.
